(57) **CLAIM**

The ornamental design for a bento box food container, as shown and described.

DESCRIPTION

FIG. 1 is a side, top perspective view of a bento box food container showing our new design;

FIG. 2 is a side, bottom perspective view thereof;

FIG. 3 is a top plan view thereof;

FIG. 4 is a bottom plan view thereof;

FIG. 5 is a side elevational view thereof;

FIG. 6 is a cross-sectional view taken along the line 5-5 of FIG. 5;

FIG. 7 is a side, top perspective view of a bento box food container shown in FIG. 1;

FIG. 8 is a side plan view thereof; and,

FIG. 9 is a cross-sectional view taken along 8-8 of FIG. 8.

The broken lines showing a jar in FIGS. 7-9 of the bento box food container are for the purpose of illustrating environment, and form no part of the claimed design.

1 Claim, 9 Drawing Sheets
